PROCESS OF PREPARING PURIFIED CHLORTETRACYCLINE HYDROCHLORIDE

John Joseph Bernardi, Pearl River, N.Y., assignor to American Cyanamid Company, New York, N.Y., a corporation of Maine
 No Drawing. Filed May 4, 1959, Ser. No. 810,593
 1 Claim. (Cl. 260—559)

This invention relates to an improved process of preparing purified chlortetracycline hydrochloride and more particularly is concerned with an improved process of recrystallizing chlortetracycline so as to produce an improved product for use in topical ointments.

One of the best procedures for purifying chlortetracycline is disclosed in the United States patent to Winterbottom et al., No. 2,671,806. The process therein disclosed involves dissolving crude chlortetracycline in a hydroxylated organic solvent by the use of a nitrogenous base, filtering off the insoluble impurities, and precipitating chlortetracycline hydrochloride therefrom by the addition of a hydrochloric acid. This process results in a pharmaceutical grade of chlortetracycline hydrochloride 95—97% pure which is suitable for parenteral administration.

However, for certain purposes, as in the preparation of topical ointments such as are disclosed in the Burkhardt et al. Patent No. 2,640,801, it is desirable that a high purity finely-powdered chlortetracycline hydrochloride salt be used or otherwise irritation occurs.

One of the commonly used tests for irritation is the rabbit intradermal irritation test. This test is a qualitative test where two reference preparations are used, a "good" or non-irritating standard and a "bad" or irritating standard.

Rabbits of medium weight, preferably chinchillas, with skins of medium thickness and without undue vascularity are used. The day before use, the entire abdominal surface is clipped with an electric clipper. Just prior to injection, the rabbits are anesthetized with sodium pentobarbital injected in the ear vein. A 0.5 percent test solution of each sample of chlortetracycline hydrochloride is prepared by dissolving 50 milligrams of the compound in 10 milliliters of pyrogen-free distilled water. Standard "good" and "bad" test samples are prepared in the same way. In all cases, vigorous shaking for one minute or longer may be necessary.

One-milliliter tuberculin syringes fitted with $\frac{3}{8}$ -inch, 27-gauge needles with intradermal bevels are used. 0.1 milliliter of each of the four solutions ("good" standard, "bad" standard and the two test samples) are injected as superficially as possible, just laterally to the mammary glands, outside the nipple line, and not in proximity to the movable skin near the fore and hind legs. A separate needle and syringe is used for each solution. The pattern of injection in each rabbit is as follows:

HEAD

"Bad" Standard	—0	0—	"Bad" Standard
Test Solution	—0	0—	Test Solution
No. 2			No. 1
"Good" Standard	—0	0—	"Good" Standard
(TAIL)			

The results are determined 16 to 20 hours after injection. A value of 1.0 is assigned to the "good" standard, and a value of 4.0 is assigned to the "bad" standard. The reaction of the rabbits to the test solutions are compared to the standards and are assigned values between 1.0 and 4.0. The values obtained from three rabbits for each solution are added together and classified as follows:

2

Numerical Value	Class
2 to 5.9.....	I. Suitable for use in any product.
6 to 9.....	II. Suitable for use in all products except those for intravenous or topical use.
9.1 to 12.....	III. Unsatisfactory.

It is important that "good" and "bad" standards show fairly typical reactions, although some variation in sensitivity of rabbits may affect this picture slightly. The important factor in reading the test is that the difference between the "good" and "bad" reactions must be marked so that the intermediate reactions may be properly evaluated.

10 15 It has been found that for some unknown reason chlortetracycline hydrochloride prepared by the Winterbottom et al. process does not consistently pass this test with a rating of II, which would be suitable for use in most products although parenteral use and use in mastitis ointments 20 require a class I rating. In many instances it has been found necessary to subject this product to further purification steps in order to produce products which are satisfactory for use in topical ointments.

25 In accordance with the present invention it has been discovered that by crystallizing the chlortetracycline hydrochloride crystals from a butanol-water-lower alkoxy lower-alkanol solvent combination a superior grade of chlortetracycline hydrochloride crystals are unexpectedly obtained which consistently pass the test for use in topical ointments with the rating of II and in many instances with a superior rating of I.

30 The present invention follows the procedure set forth in the Winterbottom et al. patent. The resulting chlortetracycline hydrochloride salt is then redissolved in a lower-alkoxy lower-alkanol solvent-water mixture by the use of a nitrogenous base. Any of the nitrogenous bases such as triethylamine, for example, specified in the Winterbottom et al. patent may be used. Suitable lower-alkoxy lower alkanol solvents are 2-methoxyethanol, 2-ethoxyethanol, etc. The insoluble impurities are then removed by filtration and the separated insolubles are washed with butanol, for example, n-butanol. The filtrate and wash liquid are combined and hydrochloric acid is added thereto to induce crystallization and precipitation of the purified chlortetracycline as a hydrochloride salt. The chlortetracycline hydrochloride is thereafter washed and dried in the usual manner to obtain a high yield of a therapeutically effective and acceptable product.

35 40 45 The proportions of lower-alkoxy lower-alkanol solvent, water and butanol may vary within rather narrow limits. Preferably, the recrystallizing solution consists of 20—35% n-butanol, 20—25% water and 50—60% 2-ethoxyethanol. The pH of this solution is preferably adjusted to a pH of between 0.5 to 2.5 with hydrochloric acid to precipitate purified crystals of chlortetracycline hydrochloride.

50 55 The invention will be described in greater detail in conjunction with the following specific examples.

EXAMPLE 1

Recrystallization of crude chlortetracycline hydrochloride

An 85 kilogram portion of crude product, assaying 880 mcg. of chlortetracycline hydrochloride per milligram, was slurried in 451 liters of the second recrystallization 65 mother liquor from a previous batch. The composition of this mother liquor was 21% n-butanol, 22% distilled water, and 57% 2-ethoxyethanol. The slurry was chilled to 4° C. and the chlortetracycline hydrochloride was 70 caused to dissolve by adding 2 moles of triethylamine per 1 mole of chlortetracycline based on a wet assay of the crude product. The pH of the solution was adjusted to

0.8 with hydrochloric acid and the solution was aged for 16 hours with continuous agitation. The crystals which formed were collected by filtration, then slurried in 203 liters of 2-ethoxyethanol and 9.75 liters of distilled water. This slurry was chilled to 2° C. and solution of the chlortetracycline hydrochloride accomplished again by the addition of triethylamine. A 1.87 kilogram quantity of activated carbon and 3.9 kilograms of Hyflo Super-Cel were added to the solution and this sludge filtered through a sparkler filter into a tank containing 67.6 liters of distilled water. The filter cake was rinsed with 117.5 liters of n-butanol and this rinse added to the filtrate. The pH of this combined filtrate and wash was adjusted to 2.5 ± 0.1 with hydrochloric acid and the solution aged 11 hours with continuous agitation. The crystals were collected by filtration, and the filtrate saved for recirculation. The collected crystals were reslurried in 91.3 liters of 2-ethoxyethanol, filtered, and the filtrate discarded. The crystals were then reslurried in 97.5 liters of distilled water, the pH adjusted to 1.3 with hydrochloric acid, and aging allowed to proceed for 1 hour. The crystals of chlortetracycline hydrochloride were collected by filtration, the filtrate discarded, and the crystals dried at 60° C. in a forced hot air dryer. The product yield was 85%.

EXAMPLE 2

The procedure of the preceding example was used in the preparation of several batches of chlortetracycline hydrochloride. A like number of batches of chlortetracycline hydrochloride were prepared following the procedure of the aforesaid Winterbottom et al. patent. The results obtained and the ratings determined by the rabbit intradermal irritation test are shown below.

TABLE

Process of Patent No. 2,671,806			New Process	
	Batch No.	Rating (Rabbit Skin Test)	Batch No.	Rating (Rabbit Skin Test)
10	1186	II	1266	II
	1188	II	1276	I
	1196	III	1287	I
	1211	III	1290	I
	1214	III	1294	II
	1217	III	1295	II
	1252	III	1306	II
	1254	II	1320	II

15 The above data clearly show products prepared according to the new method had a rating of I to II in all instances which means that the products are useful in any pharmaceutical preparation whereas the products prepared according to the patented process varied in ratings from II and III and which means rejection of some of these batches for use in topical ointments.

I claim:

25 The process of preparing purified chlortetracycline hydrochloride which comprises dissolving crude chlortetracycline hydrochloride in a mixture of 20-35% butanol, 20-25% water and 50-60% 2-ethoxyethanol by the addition of triethylamine and adjusting the pH of the resulting solution to a pH of between 0.5 to 2.5 with hydrochloric acid so as to precipitate purified crystals of chlortetracycline hydrochloride therefrom.
